CLAIM

The ornamental design for a capture card, as shown and described.

DESCRIPTION

FIG. 1 is a perspective view of a capture card showing my design;

FIG. 2 is a front elevation view thereof;

FIG. 3 is a back elevation view thereof;

FIG. 4 is a left side view thereof;

FIG. 5 is a right side view thereof;

FIG. 6 is a top plan view thereof; and,

FIG. 7 is a bottom plan view thereof.

The dashed or broken lines shown in the drawings depict portions of the capture card in which the design is embodied that form no part of the claimed design.

1 Claim, 7 Drawing Sheets
